UNITED STATES PATENT OFFICE

ROBERT C. SPRAGUE, OF QUINCY, MASSACHUSETTS

MULTIPLE CONDENSER

Application filed April 13, 1928. Serial No. 269,701.

This invention is particularly applicable to condensers such as that disclosed in my companion applications Serial No. 135,842, filed September 14, 1926, and Serial No. 239,684, filed December 13, 1927, although it is to be understood that the present invention is applicable to other condensers as well. The object of the invention is to provide a single unitary condenser which may be used as two or more condensers, as for example in circuits requiring two like condensers, and to provide such a condenser which is simple and economical to construct but which is efficient and durable in use, which does not require a metal container or other housing such as ordinarily employed, which has an effective and permanent electrical contact between the terminals and conductive layers, which has durable terminals permanently anchored in the body of the condenser so as not to break off or pull out, which is free from the likelihood of short circuit, and generally to improve the art of multiple condensers.

Prior to the invention of the aforesaid application it was customary to house condensers of the wound foil type in a tin can or other rigid container and to mount the condenser terminals on the container, the wound condenser inside the container merely being provided with light terminal strips for connecting the foil strips with the terminals on the container. This practice has not only greatly increased the cost of material and labor in the process of manufacture but it has added largely to the bulk and weight of the resulting product. Moreover, the aforesaid terminal strips connecting the foil strips with the container terminals have been very thin, being little if any heavier than the foil windings, so that they often tear off or pull out in assembling or repairing a condenser, the strips necessarily being soft and thin to avoid cutting the foil wound therearound.

In this improved condenser the container and second set of terminals carried thereby are eliminated by mounting heavy terminal strips directly in the body of the condenser in such a way that they do not tend to puncture the insulating strips between the foil strips, do not pull out, and therefore serve as

the ultimate terminals of the condenser, even to the extent of supporting the condenser as is often desirable in radio sets. This is preferably accomplished by pressing the relatively heavy terminal strips into recesses in a base, which preferably is in the form of a plate of fiber board or the like, or by striking up projections on the terminal strips which either pinch the base or wedge into recesses previously formed in the base. The inner ends of the foil strips are preferably inserted under the terminals respectively before the latter are pressed into the base, thereby anchoring the ends of the foil strips (and their intermediate insulating strips) to the core, which greatly facilitates the process of winding the strips on the base.

According to this invention a multiple condenser may have any desired number of conducting plates or foil strips, for example two or three short strips wound end to end with gaps between adjacent ends and a long common strip extending between successive turns of the short strip windings in succession. If the respective sections of the condenser are to have equal capacity the short strips should have the same length; otherwise the capacity of the respective sections may be adjusted as desired by predetermination of the lengths of the short strips. Each foil strip has a terminal strip contacting therewith and projecting from one end of the condenser, the terminals being mounted on base means embedded within the windings and having sufficient stiffness to lend rigidity to the assembly and to hold the terminals in position, preferably without the assistance of an outer container for the assembly. When using fiber board plates for the base means the plates preferably are disposed in parallel superposition with some of the windings extending between the plates and other turns surrounding a plurality of the plates, the number of plates usually being equal to or one less than the number of condenser sections. For example, both a double and a triple condenser may have two plates, a quadruple condenser three plates, etc.

For convenience the plate having the most windings therearound is referred to as the

inner plate and the plate having only a portion of the strips therearound is referred to as the outer plate; and in the preferred mode of winding the procedure is as follows: The long common strip is first anchored to the inner plate and wound therearound a number of times depending upon the desired capacity, a second strip being wound in parallel superposition therewith. After the desired number of turns a second base plate is laid on one of the flat sides of the condenser between said two strips and the second strip is anchored to the second base plate by two spaced terminals, a gap in the foil between the two terminals being formed either before or after the terminals are applied, as by severing the foil and spacing the ends before the terminals are applied or by removing a short section of the foil either before or after the terminals are applied. When the foil has a paper backing adhering thereto as described in my prior applications, the paper may be severed and spaced with the foil or a short section of paper corresponding to the said short section of foil may be removed, but preferably only the foil section is removed so that the paper backing continues unbroken. The winding of the two foils is then continued, preferably in the same direction, until the requisite number of turns have been applied, whereupon the foils are cut off, a wrapper applied, etc., as described in said applications.

With only one break in the outer foil as above described a double condenser results. To form a triple condenser it is only necessary to make a second break in the same foil strip intermediate the inner end and the first break, in which case a fourth terminal is applied to the inner end of the strip. Thus the two terminals on the inner base plate contact with the inner ends of the common strip and the first short section, while the two terminals on the outer base plate contact with the outer end of the second short section and the inner end of the third short section respectively.

For the purpose of illustration I have shown certain concrete embodiments of the invention in the accompanying drawings in which:

Fig. 1 is a side elevation of one embodiment;

Fig. 2 is a plan view of the same embodiment;

Fig. 3 is a section on the line 3-3 of Fig. 2;

Fig. 4 is a side elevation of another embodiment;

Fig. 5 is a plan view of the other embodiment;

Fig. 6 is a section on the line 6-6 of Fig. 5; and

Fig. 7 is a perspective view of the second embodiment.

In the particular embodiment shown in Figs. 1, 2 and 3, the aforesaid base plates are shown at C and C', the terminals or terminal members at 1, 2, 3 and 4, the inner or long common foil strip at F, its associated paper strip at P, the first short foil strip at F', its associated paper strip P', the second foil and paper strips at F'' and P'', the third foil and paper strips at F''' and P''' and the outside wrapper at W, the gaps between the ends of strips F' and F'' and between F'' and F''' being shown at G and G' respectively. As stated above, the paper backing for the foil strips is preferably cemented thereto by paraffin or the like as described in my prior applications so that each pair of foil and paper strips may be wound as a single unitary strip; and the paper backing of the foil sections F', F'' and F''' is a single piece of paper extending continuously throughout the length of all of these sections as well as across the gaps therebetween. The parts may be assembled as follows:

One end of a combined foil and paper strip is laid over one of the recesses in the base plate C with the foil outermost and the terminal 1 is then pressed into the recess with the projections 5 thereon fitting into the recesses 6 sufficiently tightly to hold the terminal in position, assisted if desired by a fairly snug fit of the terminal in its recess in the base. Another pair of foil and paper strips is then applied over the first pair, the second pair either being anchored by a terminal 2 as shown in Fig. 3 or merely being folded over as shown in Fig. 6, depending upon whether or not it is desired to have the terminal for this pair mounted on the first base plate C or the second base plate C'. The two pairs of strips are then wound about the core or base C in a counterclockwise direction throughout any desired number of turns, depending upon the desired capacity of the condenser. After the proper number of turns have been wound on the core C the base plate C' is applied in the position shown in Fig. 3 between the two pairs of strips with the outer pair mounted at spaced intervals on the core C' by means of the terminals 3 and 4, a section of the foil strip being removed at G' either before or after the terminals 3 and 4 are applied as above described. The two pairs of strips are then wound about both core plates in the same direction until the desired number of turns are applied, whereupon the strips are cut off and the wrapper W applied as described in my previous application. The entire assembly preferably is impregnated as described in said application to form a solid unitary assembly.

By removing a section of the foil F' during the winding process, as illustrated at G, a three-section condenser will result, the foil F constituting the common foil and the foils F', F'' and F''' constituting three separate

foils cooperating with the common foil. If only a two-section condenser is desired the gap G is omitted, in which case either the terminal 2 or the terminal 3, preferably the former, may be omitted, or, as shown in Fig. 6, one of these terminals, for example the terminal 2, may be mounted in the core out of contact with the foil so as to serve as a dummy terminal for mounting purposes.

The modification shown in Figs. 4 to 7 inclusive is similar to that above described with the following exceptions. The terminals 1' and 2', corresponding to 1 and 2 in Figs. 1, 2 and 3, have oblique portions mounted in oblique recesses in the associated core or base plate as described in said prior application, Serial No. 239,684. While the terminals 3' and 4' may be mounted in like manner, they are shown as mounted in the same manner as the terminals illustrated in Figs. 1, 2 and 3, differing only in the contour of their projecting end portions. In this modification the terminal 2' is not connected to any of the foils, being intended merely as a dummy terminal for mounting purposes, as for example in the position illustrated in Fig. 7. In this modification the terminal 1' constitutes the common terminal and the terminals 3' and 4' the terminals individual to the two sections.

I claim:

1. A condenser assembly comprising supporting means having sufficient stiffness to lend rigidity to the assembly, three or more strips of foil wound on said means with insulation therebetween, and terminal members held in position by said means in contact with said strips respectively, certain of the foil strips passing over certain of the terminal members with the outer surfaces of the latter substantially flush with the outer surfaces of said supporting means so as not to cut the strips passing thereover.

2. A condenser assembly comprising supporting means having sufficient stiffness to lend rigidity to the assembly, three or more strips of foil wound on said means with insulation therebetween, two of said strips being spaced endwise with a gap therebetween, and terminal members disposed in recesses in said means and contacting with said strips respectively.

3. A condenser assembly comprising supporting means having sufficient stiffness to lend rigidity to the assembly, three or more strips of foil wound on said means with insulation therebetween, and stiff terminal members mounted on said means inside the assembly and contacting with said strips respectively, the members having projections extending through the strips into said means.

4. A condenser assembly comprising a plurality of core members to lend rigidity to the assembly, strips of foil wound around said members, a portion of the foil wound around

only one member and another portion wound around both members and said portion.

5. A condenser assembly comprising a plurality of insulation plates in parallel superposition, strips of foil wound around said plates, a portion of the foil wound around only one member and another portion wound around both members.

6. A condenser assembly comprising a plurality of core members to lend rigidity to the assembly, a strip of foil wound around one member and thence around both members, and another strip wound around both members.

7. A condenser assembly comprising a plurality of insulation plates in parallel superposition, a strip of foil wound around one plate and thence around the other plate, the second strip wound around the first plate only, and a third strip wound around both plates.

8. A condenser assembly comprising a plurality of insulation base plates in parallel superposition, three or more strips of foil wound on said plates with insulation therebetween, and terminal members having parts extending into recesses on the outer surfaces of said plates and contacting with said strips respectively.

9. A condenser assembly comprising a plurality of insulation base plates in parallel superposition, terminal members associated with said plates respectively, a strip of foil wound around one plate and contacting with one of said members, another strip of foil wound first around one of said plates and thence around both plates and contacting with another of said members, and a third strip of foil wound around both plates and contacting with a third terminal member inside said first foil winding.

10. A condenser assembly comprising inner and outer insulation base plates, a terminal member mounted on the inner plate, a second terminal member mounted on one of said plates, and a third terminal member mounted on the outer plate, a strip of foil wound around the inner plate and thence around both plates and contacting near its inner end with the first terminal member, a second strip of foil wound around the inner plate and contacting with the second terminal member, and a third strip of foil wound around both plates and contacting near its inner end with the second plate.

11. A condenser assembly comprising supporting means having sufficient stiffness to lend rigidity to the assembly, three or more strips of foil wound on said means with insulation therebetween, a plurality of said strips being disposed end to end, and stiff terminal members mounted on said means inside the assembly and contacting with said strips respectively, the members having pro-

jections extending through the strips into said means.

12. A condenser assembly comprising a plurality of insulation base plates in parallel superposition, three or more strips of foil wound on said plates with insulation therebetween, a plurality of said strips disposed end to end, and terminal members having parts extending into recesses in said plates and contacting with said strips respectively.

10 Signed by me at Quincy, Massachusetts,
this 11th day of April, 1928.
